US00D841609S

(12) **United States Design Patent** (10) Patent No.: **US D841,609 S**
(45) Date of Patent: **** Feb. 26, 2019**

(54) **TELEVISION APPARATUS**

(71) Applicant: **LG ELECTRONICS INC.**, Seoul (KR)
(72) Inventors: **Taeho Kim**, Seoul (KR); **Jongchul Kim**, Seoul (KR); **Bumsang Lee**, Seoul (KR); **Byungmu Huh**, Seoul (KR)
(73) Assignee: **LG ELECTRONICS INC.**, Seoul (KR)

(**) Term: **15 Years**

(21) Appl. No.: **35/503,736**

(22) Filed: **Mar. 29, 2017**

(80) **Hague Agreement Data**

Int. Filing Date: **Mar. 29, 2017**
Int. Reg. No.: **DM/095492**
Int. Reg. Date: **Mar. 29, 2017**
Int. Reg. Pub. Date: **Sep. 29, 2017**

(30) **Foreign Application Priority Data**

Sep. 30, 2016 (KR) 30-2016-0047384
(51) LOC (11) Cl. **14-03**
(52) U.S. Cl. ..... USPC **D14/126**
